Des. 188,362
Patented July 5, 1960

188,362

CONTROL PANEL FOR COOKING RANGE OR THE LIKE

Emery J. Poracki, South Gate, Calif., assignor to O'Keefe
& Merritt Company, Los Angeles, Calif., a corporation
of California

Filed Jan. 13, 1958, Ser. No. 49,240

Term of patent 14 years

(Cl. D81—25)

Fig. 1 is a top perspective view of a control panel for cooking range or the like showing my new design;

Fig. 2 is a top plan view thereof;

Fig. 3 is a longitudinal, sectional view of the control panel for cooking range or the like taken on the line 3—3 of Fig. 1 in the direction of the arrows;

Fig. 4 is an end elevational view thereof; and

Fig. 5 is a cross-sectional view taken on the line 5—5 of Fig. 1 in the direction of the arrows.

I claim:

The ornamental design for a control panel for cooking range or the like, as shown.
